MORRIS HEICHEN, OF BROOKLYN, NEW YORK.

ELECTRIC-FIXTURE MOUNT.

Application filed July 24, 1926. Serial No. 124,634.

This invention relates to electric switches, and particularly to a combined switch and mounting for side wall fixtures. The purpose of the invention is to provide a simple 5 compact switch which is applicable to a wide variety of side wall fixtures, and which itself serves as an adjustable connecting means for mounting the fixture in place.

The switch is formed with a body having 10 a threaded tubular neck which is clamped by means of a nut in an aperture through the front of the escutcheon plate forming part of the fixture. The movable switch element is rotary and tubular and thus offers a passage 15 for a connecting screw which is inserted through the tubular switch member, engages the rear of the switch body and is threaded into a special fitting on an ordinary fixture stud. After the fixture is in place an actuating knob may be mounted on the forward 20 end of the tubular stem, thus concealing the screw and affording a good grip for use in actuating the switch.

The advantage of the arrangement is that 25 the switch may be assembled with the fixture and electrically connected very conveniently and rapidly, after which the switch and fixture are fastened in place by merely inserting a screw through the stem of the switch 30 and turning this into a fitting mounted on the fixture stud.

A preferred embodiment is illustrated in the accompanying drawings, in which—

Figure 1 is a perspective view of the fixture having the switch attached.

Figure 2 is a vertical axial section on a larger scale.

Figure 3 is a section on the line 3—3 of Fig. 2.

Figure 4 is a perspective view of the rotary switch contactor.

An ordinary fixture stud is shown at 6, and threaded on this is a cap 7 to which the switch mechanism hereinafter described is 45 connected. The escutcheon plate or shell of the side wall fixture is shown at 8, and obviously may take various forms, that illustrated being typical. At some appropriate point, usually the center, the escutcheon 50 plate 8 is formed with an opening having an inwardly projecting flange 9. A metallic switch casing 10, preferably circular in contour and having a threaded reduced neck 11, is mounted within the flange 9, the neck 11, 55 projecting through the opening within the flange and being retained by a nut 12

threaded thereon at the front of the escutcheon plate 8. The rear end of the shell 10 is outwardly flanged and connected to this flange by means of bolts 13 is a retaining ring 14 which locks a circular insulating body 15 within the shell 10. The insulating body 15 supports the mechanism for a known type of snap switch which comprises four ratchet teeth 16 formed on the inner face of the insulating body and opposed metal contacts 17 mounted in two of the ratchet teeth. Binding screws 18 serve as a convenient means for connecting the lead wires 19 to the switch contacts.

Swiveled in the neck 11 is a tubular switch stem 20 which is formed at its rear end with an enlarged head 21 for the purpose of preventing the stem 20 from moving outward through the neck 11. This head 21 carries a metal contactor 22 comprising an annular cup shaped sheet metal member slotted to form two outwardly sprung contactor tongues 23. The contactor 22 is pinned as shown at 24 to the head 21 of the switch stem 20. As the switch stem is turned clockwise the contactor tongues 23 snap simultaneously into and out of contact with the contact 17. The switch unit is connected with the cap 7 by means of a screw 25 which is inserted from the front through the tubular stem 20 and which enters a hole threaded to receive it in the front of the cap 7. A bushing or spacer 26 may be used beneath the head of the screw 25 so that the head of the screw is nearer the forward end of the switch stem 20 and hence more accessible.

This construction has another desirable feature, in that the bushing 26 serves as a journal to center the switch stem 20. In the example illustrated the switch stem 20 is shown as composed of insulating material, but the only essential condition is that the stem be insulated in some way from the contactor 22.

As stated, it is preferred to mount removably on the forward end of the stem 20 an actuating button. A convenient way is to thread the stem 20 as shown at 27 and to screw onto these threads an actuating button 28, but various other arrangements will suggest themselves and may be used.

The mode of applying the switch is as follows: The actuator button 28 and nut 12 are removed. All electrical connections to the switch and fixture are made. The neck 11 is inserted through the aperture in the plate 8,

nut 12 is applied and turned flush with the end of the neck. Then the screw 25 with its bushing 26 is inserted and the screw 25 is turned into the threaded hole in the cap 7 until the escutcheon plate 8 is drawn snugly against the wall in proper position. The actuator button is then screwed on and the work of mounting is complete.

The important feature of the invention is 10 that the switch body is connected to the fixture and that the fixture and switch are connected to the stud by a screw inserted from the front through a hollow actuator so as to connect the switch to the stud. The addition 15 of the actuator knob provides an attractive finish and permits ready access to the screw on occasion.

Obviously various different types of switch may be used.

20 What is claimed is:

1. In an electric switch, the combination of a casing provided with switching contacts and having an aperture to receive a screw for fixing said casing in place; a switching 25 element including a tubular actuator open at both ends and guided in a portion of said casing, the bore of said tubular actuator being alined with the aperture in said casing and so dimensioned as to permit the insertion 30 of said screw.

2. In an electric switch, the combination of a casing provided with switching contacts and having an aperture to receive a screw for fixing said casing in place; a rotary 35 switching element including a tubular actuator open at both ends and swiveled in a portion of said casing, the bore of said tubular actuator being alined with the aperture in said casing and so dimensioned as to permit the insertion 40 of said screw.

3. In an electric switch, the combination of a casing provided with switching contacts and having an aperture to receive a screw for fixing said casing in place; a rotary 45 switching element including a tubular actuator open at both ends and swiveled in a portion of said casing, the bore of said tubular actuator being alined with the aperture in said casing, and larger than said aperture; 50 and a bushing swiveled in said actuator and having a bore of substantially the same size as said aperture, the parts being so constructed and arranged that said screw when inserted supports the bushing and the bushing 55 serves as a journal for said tubular actuator.

4. In an electric switch, the combination

of a casing provided with switching contacts and having an aperture to receive a screw for fixing said casing in place; a rotary 60 switching element including a tubular actuator open at both ends and swiveled in a portion of said casing, the bore of said tubular actuator being alined with the aperture in said casing and so dimensioned as to permit the entrance of said screw; and an actuating knob removably mounted on the outer end of said actuator and serving to close the end of the bore thereof.

5. In an electric switch, the combination 70 of a casing provided with switching contacts and having an aperture to receive a screw for fixing said casing in place, said casing being formed with a reduced externally threaded neck axially alined with said aperture; and a rotary switching element including a tubular actuator open at both ends 75 swiveled in said neck, the bore of said tubular actuator being so dimensioned as to permit the entrance of said screw.

6. In an electric switch, the combination 80 of a casing provided with switching contacts and having an aperture to receive an attaching screw for fixing said casing in place, said casing being formed with a reduced threaded extension axially alined with said aperture; a rotary switching element including a tubular actuator open at both ends and swiveled in said threaded extension, the bore of the tube 85 being larger than said aperture; and a bushing swiveled in said actuator and having a bore of substantially the same size as said aperture, the parts being so constructed and arranged that the attaching screw when inserted supports the bushing and the bushing 90 serves as a journal upon which said tubular actuator is rotatably mounted.

7. In an electric switch, the combination 95 of a casing provided with switching contacts and having an aperture to receive a screw for fixing said casing in place, said casing being formed with a reduced externally threaded neck axially alined with said aperture; a rotary switching element including a tubular actuator open at both ends swiveled 100 in said neck, the bore of said tubular actuator being so dimensioned as to permit the entrance of said screw; and an actuating knob removably mounted on the outer end 105 of said tubular actuator and closing the bore 110 thereof.

In testimony whereof I have signed my name to this specification.

MORRIS HEICHEN.
